US00D551816S

(12) **United States Design Patent** (10) Patent No.: **US D551,816 S**
(45) Date of Patent: **** Sep. 25, 2007**

(54) **DISPLAY/INPUT FIELD**

(75) Inventor: **Joerg Schroeter**, Groebenzell (DE)

(73) Assignee: **BSH Bosch und Siemens Hausgeraete GmbH**, Munich (DE)

(**) Term: **14 Years**

(21) Appl. No.: **29/254,805**

(22) Filed: **Feb. 27, 2006**

(30) **Foreign Application Priority Data**

Aug. 29, 2005 (EM) 000400296

(51) **LOC (8) Cl.** **15-05**

(52) **U.S. Cl.** **D32/31; D32/28**

(58) **Field of Classification Search** D32/21, D32/23-25, 28, 31; 15/319-320, 327.1, 15/327.2, 327.6, 327.7, 358, 340.1; 901/1, 901/47; 700/245, 259; 318/568.12; 180/168, 180/169, 204, 274; 701/23

See application file for complete search history.
